ELASTIC FLUID TURBINE BLADING

Filed Jan. 21, 1942

UNITED STATES PATENT OFFICE

2,355,413

ELASTIC FLUID TURBINE BLADING

David J. Bloomberg, Newton, Mass., assignor to
General Electric Company, a corporation of
New York

Application January 21, 1942, Serial No. 427,601

6 Claims. (Cl. 253—77)

The present invention relates to elastic fluid turbine blading, more specifically to blading of rotary bucket wheels. In elastic fluid turbines designed for constant speed and pressure conditions it has been the practice heretofore to provide bucket blades substantially crescent-shaped in cross-section and with constant entrance angle along their entire length except in the case of bucket blades used for low pressure turbine stages where in certain instances it has been customary to take into consideration the difference between the rotational speed of the outer and inner portions of such buckets and vary the entrance angle accordingly. It has been found that aside from differences in differential speed present arrangements of turbine blading do not take into consideration changes in elastic fluid velocities due to friction at the inner and outer walls of nozzles for directing elastic fluid towards the bucket blades. The buckets ordinarily are designed to attain best efficiency with regard to the elastic fluid velocity obtaining in the central or major portion of the nozzles.

The object of my invention is to provide an improved construction of elastic fluid turbine blading whereby each bucket portion is designed for best efficiency with regard to the elastic fluid velocity existing near such portion.

For a consideration of what I believe to be novel and my invention, attention is directed to the following description and the claims appended thereto in connection with the accompanying drawing.

In the drawing Fig. 1 illustrates a sectional view, partly broken away, of an elastic fluid turbine embodying my invention; Fig. 2 is an explanatory view; Figs. 3, 5 and 7 are perspective views of three modifications according to my invention; and Figs. 4, 6 and 8 are top views of the blades in Figs. 3, 5 and 7 respectively.

The arrangement in Fig. 1 comprises a bucket wheel 10 having a ring or disk 11 with a plurality of circumferentially spaced buckets 12 attached thereto. The blades of the buckets 12 will be described hereafter. During operation elastic fluid is directed towards the bucket 12 by a nozzle diaphragm 13 and the elastic fluid discharged from the bucket wheel is passed to another bucket wheel through the intermediary of another nozzle diaphragm 14 having a plurality of circumferentially spaced partitions 15 held between an inner disk 16 and an outer ring 17. The diaphragms 13 and 14 are supported on an outer casing or shell 18. The partitions of the dia-

phragm 13 in the present example overlap with the bucket 12 of the bucket wheel 10.

Adjacent partitions 15 form nozzles or passages for properly directing elastic fluid from one bucket wheel to a succeeding bucket wheel. The velocity of elastic fluid passing through a nozzle formed between partitions 15 is approximately constant over an intermediate portion of the nozzle area between the inner and outer diameters extending over a length of about 80% of the entire length of the partition 15. The velocity near the inner and outer portions of the nozzle decreases due to friction along the end walls of the nozzle and other sources of losses and becomes zero at the end wall. In Fig. 1 the dot-and-dash line 20 is a typical velocity curve plotted over the radial length of a nozzle between the inner and outer diameters. The velocity v_1 for the intermediate portion of the nozzle, as stated above, is substantially constant. The velocity v_2 for the end portions of the nozzle decreases from v_1 to zero at the nozzle wall.

In the velocity diagram of Fig. 2 the vector w designates the wheel speed. The vectors v_1 and v_2 designate average velocities of the elastic fluid in the intermediate portions and the end portions respectively of the nozzle. The resultant of the vectors w and v_1 is x_1 and its angle towards the horizontal, that is the angle at which elastic fluid is discharged from the nozzle and enters the bucket passages, is designated with α_1 . The resultant of the vectors w and v_2 is designated with x_2 . Its angle towards the horizontal is α_2 . In order to obtain best efficiency for an elastic fluid velocity x_1 at an angle α_1 the bucket blade should have an entrance angle equal to α_1 . Such a bucket blade is indicated in Fig. 2 in cross-section by reference numeral 21. With such cross-section best efficiency is obtained with regard to the intermediate portion only of the nozzle. In order to attain similar good efficiency for the reduced steam velocities near the end portions of the bucket blade I provide these end portions with entrance angles α_2 . In Fig. 2 I have shown with regard to the vector x_2 a cross-section 22 of a blade portion having an entrance angle α_2 . Thus, a blade according to my invention has an intermediate portion with a cross-section 21 and an end portion with a cross-section gradually merging from the cross-section 21 to the cross-section 22. The cross-section 21 has a sharp inlet edge with an entrance angle α_1 while the cross-section 22 has a rounded inlet edge with an entrance angle α_2 . The provision of end portions with larger entrance angles is particularly effective in case

of buckets overlapping the partitions from which they receive elastic fluid as indicated in Fig. 1 with regard to the buckets 12 and the partitions of the diaphragm 13.

The bucket in Figs. 3 and 4 comprises a base 23 with a blade 24 secured thereto. The blade 24 has an intermediate portion 25 which is crescent-shaped and has a cross-section corresponding to the cross-section 21 of Fig. 2. The blade 24 has a portion 26 at each end which has a cross-section merging from a section corresponding to that of 21 in Fig. 2 towards a section or end face 27 corresponding to the section 22 in Fig. 2.

As indicated in Fig. 4 the entrance edge 28 of the bucket is uniformly spaced along its entire length from the center line of the bucket, the spacing being indicated by the reference character 29. The blade arrangement as shown in Fig. 3 is very efficient but requires more machining due to the increasing thickness of the entrance portion near the ends of the blade relative to the intermediate portion.

The arrangement in Figs. 5 and 6 requires little additional machining as compared with that of an ordinary blade with uniform entrance angle along its entire length. The bucket of Fig. 5 has a blade 30 secured to a base 31. The cross-section of the blade is essentially crescent-shaped along its entire length, as shown in Fig. 6. End portions of the entrance edge 32 of the blade are cut away, thus providing a portion with an entrance angle gradually increasing from the angle β_1 (Fig. 6) for the intermediate portion to the angle β_2 for the outer ends of the end portions. The spacing of the inlet edge of this bucket from the center line is not uniform, however. At the outer ends the blade is spaced from the center line by a distance 33 which is less than the spacing 34 for the intermediate portion. This means that the entrance edge of the outer portions of such blade will have an increased clearance from the outlet edge of the diaphragm partitions with which the blade is to be associated.

The arrangement of Figs. 7 and 8 comprises a bucket with a blade 35 fastened at its inner end to a base 36. The blade has an intermediate portion 37 extending over at least 80% of the entire length of the blade and being essentially crescent-shaped in cross-section. The blade has end portions 38, each having a length of less than 10% of the entire length of the blade. These end portions are gradually bent backward in the direction of rotation on the inlet side with regard to the intermediate portion, as shown in Fig. 2. The entrance edges of the end portions are cut away so that the entrance edge of the entire blade is uniformly spaced from its center line.

What I claim as new and desire to secure by Letters Patent of the United States is:

1. Elastic fluid turbine bucket blade for receiving elastic fluid from a diaphragm having a plurality of circumferentially spaced partitions held between inner and outer rings, such blade having an intermediate portion extending over a length of about 80% of the entire length of the blade and having a uniform crescent-shaped cross-section with a constant entrance angle and the blade having a portion at each end with an entrance angle larger than that of the intermediate portion.

2. A turbine blade of the kind described, which blade has an intermediate portion with a sharp entrance edge forming a uniform entrance angle for elastic fluid and a portion at each end with an entrance edge increasing in thickness towards the end and forming an entrance angle increasing from that of the intermediate portion towards the end.

3. A turbine blade of the kind described which has an intermediate portion essentially crescent-shaped in cross-section and having a sharp inlet edge with uniform entrance angle, and an entrance portion at each end which has a cross-section equal to a part of the cross-section of the intermediate portion with parts of both end portions near the inlet edge being gradually cut away in order to form entrance angles gradually increasing from that of the intermediate portion towards the outer ends of the end portions.

4. A turbine blade of the kind described which has an intermediate portion substantially crescent-shaped in cross-section and forming a constant entrance angle and a portion at each end also substantially crescent-shaped in cross-section and having an entrance angle which increases from the inner end of such end portion towards its outer end.

5. In a turbine, a diaphragm having a plurality of circumferentially spaced partitions and a bucket wheel having a plurality of circumferentially spaced buckets with end portions overlapping corresponding end portions of the partitions, both end portions of each bucket near its entrance edge being cut away and forming entrance angles for elastic fluid larger than the entrance angle of the intermediate bucket portions.

6. A turbine blade of the kind described, which blade has an intermediate portion with a sharp entrance edge and a portion at each end bent back in the direction of rotation with regard to the intermediate portion to form entrance angles increasing towards the outer ends of the end portions.

DAVID J. BLOOMBERG.
